UNITED STATES PATENT OFFICE.

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS.

PUMPING UNIT.

Application filed July 25, 1925. Serial No. 45,978.

This invention relates to improvements in pumping units and more particularly to a self sealing pump adapted to transport a liquid from a source of supply or storage 5 tank to the place of use or consumption.

While the most advantageous use of this improved pumping unit is set forth in describing this invention, it is to be understood that it is not limited thereto, as it can be 10 applied wherever its results are desirable and obtainable without departing from the scope of the invention.

Where a storage tank of liquid is at a distance and at a different level from the 15 place of use or consumption, a pumping unit that at all times is operative to transport such liquid is most desirable. It is an object of this invention to provide such a device that is particularly adapted to supply liquid 20 fuel at a constant rate to a burner from a distant and probably sub-surface storage tank during the operation of the fuel burning mechanism. As such devices are usually controlled by a thermostat or by the pressure or temperature generated by the heat 25 from the burner, the operation of the burner mechanism is intermittent and the supply of liquid fuel must be not only available immediately upon the starting of the operation 30 but also constant during such operation for a successful device of this character.

A preferred embodiment of this invention is illustrated upon the accompanying sheets of drawing in which:

35 Figure 1 is a view in side elevation.

Figure 2 is a top plan view of Figure 1.

Figure 3 is a bottom plan view of the same.

40 Figure 4 is a view in horizontal section taken on the lines 4-4, Figure 1, looking in the direction of the arrows.

Figure 5 is a view in vertical section taken on the line 5-5, Figure 2, looking in the direction of arrows.

45 Figure 6 is a view in end elevation of Figure 1, with parts broken away and looking from the left hand side.

The unit comprises two air tight chambers 1 and 2, preferably having cylindrical side walls 3 and 4 supported upon a common base 5 with separate top closures 6 and 7 joined to the base by a plurality of rods 8 holding the parts in air tight relation. The base is preferably mounted upon 55 supports 9 with an electric motor 10 cen-

trally secured on the under side thereof adapted to operate a rotary or other positively acting pump 11 also supported from the under side of the base 5 having a suction line 12 from chamber 2 and a delivery 13 60 into chamber 1. The suction line 12 is joined to a stand pipe 14 passing upward through the base 5 and extending within the chamber 2 to a short distance from the under side of the top closure 7 thereof. Another stand pipe 15 of similar size and height is arranged in said chamber 2, passing out 65 through the base, is joined to an intake pipe 16 leading to the source of liquid or storage tank unit shown. The delivery 13 of the pump is joined to a stand pipe 17, preferably of similar size and height to the others just described, passing upward through the base 5 within the chamber 1 to a short distance from the under side of the 70 top closure 6 thereof. Another stand pipe 18 preferably of similar size and height is arranged in said chamber 1, passing out through the base is joined to a pipe 19 which acts as an over flow and preferably 75 leads back to the storage tank. A discharge pipe 20 also leads from near the bottom of the chamber 1 through the base and is joined to a pipe 21 leading to the burner or other place of consumption. In the stand 80 pipe 14, joined to the suction line of the pump, a small opening 22 is provided near the bottom of the chamber 2, as shown in Figure 1, the purpose of which will be later 85 described.

The motor 10 is controlled by a float operated switch within the chamber 1 from which the liquid is delivered to the place of consumption. The commercial or other current is led by conduits 23 and 24 to a junction box 25 preferably arranged upon the upper surface of one of the chamber closures 6, from which extend flexible leads 26 to the poles of the motor, one of the commercial 95 leads is connected in circuit with the motor and the other is in circuit with one terminal of the control switch with the other terminal thereof in circuit with the other pole of the motor. While the float operated switch may be of any known type, a preferred form is shown in Figures 5 and 6 which includes a ball float 27 mounted for movement up and down over a vertical switch actuating rod 28 having vertical play in a sleeve 29 depending from the under side 100 105 110

of the top closure 6 of the chamber 1 and having adjustable stops 30 and 31 secured thereon above and below the float 27 adapted to be engaged by said float and moved vertically therewith. The lower end of the actuating rod pivotally engages a spring pressed switch operating lever 32 the strength of which is sufficient to support the weight of the rod above in the upper or open position. The terminals of the switch leading from the junction box 25 are preferably in the form of rods 33 and 34 having contacts at their lower ends which are closed through the operating lever 32 by the depression of the actuating rod 28 as the downward limit of the float is reached and opened by the upward movement of the float lifting the rod, as can readily be seen from Figures 5 and 6.

20 The operation of the unit is as follows: When the unit is first set up and connected to the storage tank through pipe 16 and burner through pipe 20 and the electrical connection made it is necessary for the first 25 and only time to prime the pump 11 for exhausting the air from the unit and intake pipe. As soon as the air is exhausted the liquid will be drawn from the storage tank into chamber 2 of the unit which it enters 30 as it over flows the top of the standpipe 15. The opening 22 in the stand pipe 14 from the suction line 12 is of such size that as the liquid in chamber 2 rises thereabove sufficient liquid will continuously pass through 35 this opening to form a seal for the pump 11 during its operation thereafter. The suction line stand pipe 14 being of the same height as the intake stand pipe 15 the chamber 2 is filled with the liquid before the normal operation of the unit begins. The pump 40 draws the liquid from the top of chamber 2 and delivers it into chamber 1 through the delivery stand pipe 17 until the level of the liquid therein causes the float 27 to engage the stop 30 and lift the actuating rod 28 to operate the switch to break the motor circuit.

45 During the normal operation of the burner the liquid is supplied from the bottom of chamber 1 to the burner nozzle through the discharge 21 and delivery pipe 13. As the liquid is discharged from the chamber 1 its level subsiding the ball float engaging the lower stop on the actuating rod 28 closes the motor circuit thereupon the pump will operate to fill the chamber 1 from the other 50 chamber 2 and continue to draw liquid from the storage tank into the chamber 2 until the level of the liquid in the chamber 1 has raised the float therein to engage the upper stop on the actuating rod and broken the motor circuit. The overflow stand pipe 18 is provided in the chamber 1 as a safety outlet in case the float valve should for any reason fail to break the motor circuit at the 55 proper time.

It is seen that by this construction the chamber 2 is always filled with liquid and the weight of which above the opening 22 in the suction stand pipe 14 will always provide and maintain a liquid seal for the pump 70 11 during the normal operation of the unit. It is to be understood that the liquid from the chamber 1 is delivered to the burner nozzle either by gravity or through a fuel supply means operating in conjunction with 75 the other operating mechanism of the burner, as the case may be. By this unit sufficient liquid fuel is always at hand for the initial operation of the burner, which comes within the safety fire regulation, and thereafter provides means for continuing the supply thereto from the more distant source or main storage tank. The provision of the chamber 2 of the construction specified assures the constant and instant operation of 80 the pump whenever the level of the liquid in the chamber 1 is lowered sufficiently to operate the float valve to close the motor circuit.

What I claim is:

90 1. A pumping unit for transporting and delivering liquid comprising two enclosed chambers, a pumping element connected on opposite sides to the respective chambers, pipes in each chamber from the pumping element extending adjacent the tops of said chambers, an intake pipe from the source of liquid leading into the chamber communicating with the intake side of the pumping element extending adjacent the top of said chamber and a delivery pipe leading from adjacent the bottom of the other chamber, the pipe leading to the intake of the pumping element provided with an opening adjacent the bottom on the interior of that chamber whereby the liquid is allowed to pass into the pumping element and form a liquid seal therefor.

95 100 105 2. A pumping unit for transporting and delivering liquid comprising two enclosed chambers, a pumping element connected on opposite sides to the respective chambers by pipes passing through the bottoms and terminating adjacent the tops of said chambers, an intake pipe from the source of liquid leading through the bottom of the chamber communicating with the intake side of the pumping element and terminating adjacent the top thereof, a delivery pipe leading from adjacent the bottom of the other chamber, means in connection with the pipe leading to the intake side of the pump and interior of that chamber for forming a liquid seal for said element, an electric motor for operating said pumping element, a switch in the motor circuit, and means controlled by the level of the liquid in the discharge chamber for operating said switch.

110 115 120 125 3. A pumping unit for transporting and delivering liquid comprising intake and dis-

charge enclosed chambers, a pipe from the source of fluid extending through the bottom of the intake chamber to adjacent the top thereof and a similar pipe leading from adjacent the top of that chamber through the bottom to the intake side of a pump disposed between the chambers whereby the liquid is normally maintained in that chamber to a height of the pipes, the pipe leading to the intake side of the pump provided with a small opening adjacent the bottom of the chamber whereby the column of liquid within the chamber maintains a liquid seal for said pump, a pipe leading from the discharge side of the pump to the interior of the discharge chamber terminating near the top thereof and a similar pipe leading from adjacent said top through the bottom as an overflow, a delivery pipe leading from adjacent the bottom of said chambers therethrough, an electric motor for operating the pump, a switch within the discharge chamber and in motor circuit, a float within the discharge chamber operatively connected with said switch to close the motor circuit when the liquid within that chamber reaches a predetermined low level and to break the motor circuit when the said liquid reaches a predetermined high level within the discharge chamber. 20 25

WALTER W. WILLIAMS.
